CLAIM

The ornamental design for a motion controller, as shown and described.

DESCRIPTION

FIG. 1 is a perspective view of a motion controller showing our new design;

FIG. 2 is another perspective view thereof;

FIG. 3 is still another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is a cross-sectional view taken along line 10-10 in FIG. 6.

The dashed broken lines illustrate portions of the motion controller and form no part of the claimed design. The dot-dash lines define the bounds of the claimed design and form no part thereof.
